UNITED STATES PATENT OFFICE.

JOHN A. MILLER, OF HOMEWOOD, ILLINOIS.

AMUSEMENT STRUCTURE.

Application filed July 31, 1924. Serial No. 729,248.

My invention relates to amusement structures for installation at amusement parks, pleasure resorts, fairs, etc. Generally speaking, my improved structure comprises an outer building structure built in the usual manner with its floor level and side walls perpendicular so that people observing it will see nothing out of the ordinary. Within this outer structure is placed an inner building structure or a series of rooms whose floors are inclined but whose side walls are perpendicular to the plane of the floors so that the floors and walls will always appear at right angles with each other. A person seeing the outer structure and about to enter will do so with a fixed concept of the proper horizontal and perpendicular and when he reaches the inner structure and attempts to walk across the inclined floors he will be considerably disturbed and bewildered by the effect of gravity. The effect of gravity will be at variance with his mental concept of the proper horizontal and perpendicular and this will make it difficult and bewildering for the person to proceed through the inner structure in any natural manner and passage through the structure is therefore full of sensations.

To increase the bewilderment, sensation and difficulty of progress, I place some of the side walls of the inner structure diagonally so that these walls, although still at right angles with the plane of the inclined floor will not be at right angles with the longitudinal line of the floor or the direction in which a person is traveling toward such walls.

Another feature of the invention is the provision of peep holes or passages through which persons on the outside of the structure may view the bewildering and unnatural movement of persons passing through the inside of the structure, and through which the world outside will look entirely wrong and unnatural to persons navigating through the interior structure.

My invention also comprises other features of construction and arrangement all of which tend to increase the bewildering and sensational effect during a trip through the structure. On the accompanying drawing I show a structure incorporating various features of my invention and on this drawing Fig. 1 is a side elevational view

and Fig. 2 is a plan view, Fig. 1 being in section on plane 1—1 Fig. 2 and Fig. 2 being in section on plane 2—2 Fig. 1.

The outer structure comprises the level floor 1, the perpendicular side walls 2 and 3 and the rear wall 4, the side walls terminating in ornamental pillars 5 and 6 between which extends the front wall structure 7. Along the front parts of the side walls, the partitions or inner walls 8 and 8' extend perpendicularly from the floor 1 but are set in a distance to leave entrance and exit corridors 9 and 9', the outer ends of these inset walls being connected to the front wall by the diagonal walls 10 and 10', 60 there being the entrance and exit spaces or passageways 11 and 11' to the corridors 9 and 9' respectively. The outer studs or uprights 12 together with the pillars 5 and 6 support the roof 13, while shorter studs 14 support the walls 8, 8', 10 and 10', the ceiling 15 is parallel with the floor 1. 70

14 support the walls 8, 8', 10 and 10', the ceiling 15 is parallel with the floor 1.

The inner structure comprises the two rooms A and B which communicate with each other, the room A being between the side walls 2 and 3 and the rear wall 4, and the room B being within the walls 7, 8, 8', 10, and 10'. The floor structure 16 for the room A is inclined at about an angle of 15 degrees with the main floor 1, the rear 80 end of the floor structure 16 being horizontal and resting on the supporting framework 17, while the front end of the floor coincides with the floor 1 and is horizontal, intermediate framework 18 assisting in rigidly supporting the floor structure 16. The floor structure 19 for room B is also inclined and is shown parallel to the floor structure 16, its front edge coinciding with the floor 1. The floor structure 19 is higher than the floor structure 16 and forms a 85 sort of balcony with reference to the room A. The floor 19 terminates short of the inner end of the room B and at its sides stairways 20 and 20' connect the floor structure 19 and 16, the step board 21 of the stairs being parallel with the floors and the back boards 22 being at right angles with the floors. The side walls 23 and 23' of the room B are in vertical planes and parallel 90 with the walls 8 and 8'. The walls 24, 25 and 25' are at right angles with the floor structure 19 and at their floor lines are parallel with the walls 7, 10, and 10' of the outer structure, the wall 24 at its upper 100

110

edge meeting the wall 7. The walls 23, 23', 24, 25 and 25' support the ceiling 26 which is parallel with the floor 19.

The room A has the rear wall 27, the 5 diagonal walls 28 and 28', and the front diagonal walls 29 and 29'. These walls are all at right angles with the floor 16 and the walls 28 and 28' are respectively at right angles with the walls 29 and 29'.

- 10 The floor 16 extends into the corridor spaces 9 and 9' and forms the inclines or ramps 30 and 30', the inclined surfaces preferably gradually merging into the level front part of the corridors as indicated at 15 *x* Fig. 1. The slanting walls 29 and 29' are between the incline approaches and the interior of the room A, the walls being perpendicular to the plane of the inclines but extending diagonally across. At their outer edges these walls join the front edges of the front edges of the side walls 23 and 23' of the room B. The wall 29 has the doorway 31 and a window 32, and the wall 29' has a similar doorway 31' and a window 32', the doorways and windows being parallel with the wall edges as clearly shown in Fig. 1. The walls 28 and 28' have the windows 33 and 33' respectively which are preferably opposite the windows 32 and 32' 30 respectively so that persons in the corridors or on the inclines may look through the two opposed windows. The walls 28 and 28' may also have additional windows 34.

From the inner edges of the doorways 35 hand rails 35 and 35' extend parallel with the walls 28 and 28' to form aisles 36 and 36'. Inwardly of these hand rails are the parallel hand rails 37 and 37' forming the aisle 38 and 38', the rails 37 and 37' terminating short of the walls 29 and 29' to leave passageways 39 and 39' near the stairways 20 and 20'.

The windows, doorways and boards forming the various walls are all at right angles with the floor supporting the walls so that there will be nothing to indicate that the walls are anything but plumb. Persons entering through the corridor 9 whose floor gradually merges into the incline 30 along 45 which the persons then travel toward the wall 29, the force of gravity tending to draw the person backward and this will take away some of the attention which might otherwise be directed to the slanting wall 29. Scenery or some other attraction may be placed in the spaces 40 and 40' to be visible through the windows 32 and 33 to persons traveling up the incline and this will further detract the mind. The persons 50 then enter the room A along the aisle 36 and as this aisle extends diagonally along the slanting floor 16 gravity will tend to pull the persons sideways as well as backwards and they will be lurched toward the rail 35 which they can take hold of to sup-

port and help themselves along. They then enter the aisle 38 and are drawn forwardly and sidewise by the force of gravity toward the rail 37 and when traveling through the passageway 39 they encounter the stairway 20 whose steps are inclined rearwardly. However, as the stairway is plumb with reference to the floor and sides of the room A and B and as the walls are plumb with the floor the impression given the persons is that the stairway is normal and with this concept in mind opposed by the inclination of the steps and the consequent effect of gravity the persons will be very much unbalanced and bewildered. A hand rail 41 is provided for the stairway 20. At the top of the stairway the persons reach the balcony floor 19 across which they will attempt to travel to reach the stairway 20'. During such travel they will be pulled down the incline floor and it will be only with considerable effort that the stairway 20' will be reached, and owing to the inclination of the steps which is contrary to the mental concept of the person there will be considerable sensation in going down the stairway and the hand rail 41 will be considerably used. The persons then travel through the passageway 39' and through the aisles 38' and 36' to the door 31' and then down the incline 30' and through the corridor 9' and exit passageway 11'. Upon reaching the outer corridor and the exterior of the structure everything looks as plumb as before they entered and the persons are at a loss to account for their bewilderment and sensation while traveling through the inner structure.

Various installations and arrangements may be utilized to further bewilder the persons. For example seats 42 and 43 may be provided with their seat sections parallel with the floor and their backs at right angles therewith so that relative to the floor and side walls of the rooms A and B the seats will look perfectly normal. Owing to the slant of the floor, when persons first attempt to sit down on the seat they will tip backwardly with considerable force and will have a hard time to rise up after getting seated. The floor boards 44 in the rooms instead of running longitudinally or transversely in the ordinary way, could run diagonally to the arrangement shown. All this would add to the mystery and sensation.

One of the main features of my invention is to permit persons outside of the structure to look in and observe the strange attitudes and movements of persons traveling through the structure, and also to permit persons traveling through the structure to look to the outside. Persons passing the entrance and exit passageways 11 and 11' may look through the corridors and the windows and

doorways in the walls 29 and 29' and see the persons as they enter and leave the inner structure. I also preferably provide sight ports 45 and 45' opening through the outer walls 10 and 25 and the walls 10' and 25' of the room B. Through these ports persons passing the structure may peek in and observe the unnatural progress of persons through the rooms A and B, and also persons within the room may look to the outside and to them the outside will appear all wrong. In front of the wall 7 may be placed the ticket booth 46 behind which the wall may have a sham doorway 47 with a transom 48 above it through which persons passing the booth or purchasing tickets may look into the rooms B and A, and through which persons inside the rooms may look to the outside, the appearances in either direction being unnatural.

I thus produce a bewildering, mystifying and sensational structure so arranged that persons on the outside may observe just enough of the unnatural movements of persons on the inside to induce them to go through the structure. The structure thus does its own advertising and eliminates the need of expensive special or ballyhoo advertising.

I do not desire to be limited to the exact construction and operation shown as changes may be made which will come within the scope of the invention.

I claim as follows:

1. In an amusement structure of the class described, the combination of an outer structure having plumb walls and a level floor, an intermediate structure having plumb walls and having its side walls parallel with but set in a distance from the side walls of said outer structure to leave exit and entrance corridors, a room at the end of said intermediate structure extending between the side and rear walls of said outer structure, the floor of said room sloping upwardly toward the rear wall of said outer structure, front walls for said room at the ends of said exit and entrance corridors, said walls being at right angles with the floor of said room but set diagonally transversely of said corridors, and approach inclines from the front ends of said corridors to said diagonal walls merging into the floor of said room, said diagonal walls having entrance and exit doorways respectively.

2. In an amusement structure of the class described, the combination of an outer structure having plumb walls and a level floor, an intermediate structure having plumb walls and having its side walls parallel with but set in a distance from the side walls of said outer structure to leave exit and entrance corridors, a room at the end of said intermediate structure extending be-

tween the side and rear walls of said outer structure, the floor of said room sloping upwardly toward the rear wall of said outer structure, front walls for said room at the end of said exit and entrance corridors, said walls being at right angles with the floor of said room but set diagonally transversely of said corridors, approach inclines from the front ends of said corridors to said diagonal walls merging into the floor of said room, said diagonal walls having entrance and exit doorways respectively, and a second room communicating with the front end of said first room and extending between the inset intermediate walls, the floor of said second room being parallel with, but higher than, the floor of said first room, and a stairway between said floors.

3. In an amusement structure of the class described, the combination of an outer structure having plumb walls, an inner structure comprising a main room and a balcony, the floors and ceilings of said main room and balcony being parallel but said floors being in separate planes sloping upwardly toward the rear end of the outer structure, stairways connecting said floors, said balcony part being set in a distance from the sides of the outer structure to leave entrance and exit corridors for said main room, the floors in said corridors adjacent to said main room being in the same plane as the floor of said main room, walls for said main room perpendicular to the floor thereof but diagonally across said corridors, and doorways in said diagonal walls.

4. In an amusement structure of the class described, the combination of an outer structure having a level floor and plumb enclosing walls, an inner structure in the form of a room set within the outer structure with its floors sloping downwardly from the rear end toward the front end of said outer structure, the walls of said room being vertical with its floor but being set at 45 degree angles with reference to the walls of the outer structure, the floor of said room being extended forwardly to merge into the level of the floor of said outer structure whereby to form an approach incline to said room, and a doorway in the wall of said room at the end of said incline.

5. In an amusement structure of the class described, the combination of an outer structure having a level floor and plumb walls, a corridor within said outer structure, an incline leading upwardly from the inner end of said corridor, a room within said outer structure having a wall placed at right angles with the floor plane of said inclines but extending diagonally across so that all the lines of said walls will appear perpendicular to a person walking up the incline,

and an entrance opening in said wall to said rooms the floor of said rooms, sloping in the same direction as said incline.

6. In an amusement structure of the class described, the combination of an outer structure comprising outer and inner walls forming a corridor visible from the exterior of the structure, the floor at the inner end of said corridor sloping gradually upwardly

10 in one direction to form an approach, an inner structure in the form of a room having a wall at the head of said approach placed at right angles to the floor plane of the approach but extending diagonally

15 across, an entrance opening in said wall to said room, the floor of said room sloping in the same direction as said approach, and a rear wall for said room opposite to said approach wall, said walls being at right angles

20 with each other and said rear wall being at right angles with the room floor, said rear wall being visible through said corridor from the exterior of the outer structure.

7. In an amusement structure of the class described, the combination of an outer structure having plumb walls, an inner structure comprising a main room and a balcony, the floors of said main room and balcony being parallel but sloping downwardly toward the

30 front end of said structure, the walls of said room and balcony being at right angles with the respective floors, a stairway between said floors arranged with its steps parallel with the floors, a corridor between the

35 inner and outer structures visible from the exterior of the outer structure, the inner end of said corridor sloping upwardly to merge into the floor of said main room, and an entrance wall for said inner structure set

40 diagonally across the head of said incline but at right angles with the floor of the main room.

8. In an amusement structure of the class described, the combination of an outer structure having plumb walls, an inner structure comprising a main room and a balcony, the floors of said main room and balcony being parallel but sloping downwardly toward the front end of said outer structure, a stair-

50 way between said floors, the side walls of said balcony being parallel with the side walls of said outer structure and the walls of said main room being set diagonally, all the walls of said main room and balcony

55 being perpendicular to the respective floors, a corridor between the inner and outer structures visible from the outside of the outer structure, the floor of said main room extending into said corridor to form an approach incline, one wall of said main room being at the head of said approach and having

60 an entrance opening to said main room.

9. In an amusement structure of the class described, the combination of an outer structure having plumb walls, an inner structure in the form of a room whose walls and floor are relatively plumb but which room as a whole is tilted with its floor inclined downwardly toward the front of the outer structure, an entrance passageway between said structures to said inner structure, and a sight passageway extending from the vertical wall of the outer structure to the inclined wall of the inner structure through which passageway persons outside of the outer structure may view persons passing through the inner structure and through which persons on the inside may look to the outside.

10. In an amusement structure of the class described, the combination of an outer structure having plumb walls, an inner structure having floors and walls at right angles with each other but tilted as a whole to have its floors sloping downwardly toward the front end of said outer structure whereby said inner structure will be out of plumb relative to the outer structure, one of said walls of the inner structure having an entrance opening, a corridor between said structures leading gradually up to said entrance opening and visible from the exterior of the outer structure, and vision passageway extending from the vertical wall of said outer structure to the adjacent inclined wall of the inner structure, through which passageways persons on the inside of the inner structure may be visible to persons outside of the outer structure and through which persons on the inside may look to the outside.

11. In an amusement structure of the class described, the combination of an outer plumb structure, an inner structure having parallel sloping floors spaced away from each other and walls all set at right angles to said floors, stairways connecting said different floors, a corridor between said structures, the floor of said inner structure extending into said corridor to form an approach incline, the entrance wall of said inner structure being set diagonally across the top of said incline but at right angles therewith, and an entrance opening in said wall, said wall and entrance opening being visible through the corridor from the exterior of the outer structure but appearing plumb to persons looking down the corridor whereby such persons may see others traveling along the incline and into said inner structure without being able to account for their unnatural movements.

In witness whereof, I hereunto subscribe my name this 24th day of July A. D., 1924.

JOHN A. MILLER.
